IMPEDANCE MATCHING COUPLING SYSTEM

Walter van B. Roberts, Princeton, N. J., assignor
to Radio Corporation of America, a corporation
of Delaware

Application February 7, 1936, Serial No. 62,784

6 Claims. (Cl. 178—44)

This invention relates to impedance matching coupling systems and has particularly to do with networks of that character where used in radio transmitting and receiving apparatus. One of the objects of my invention is to provide a means and a method whereby proper adjustment of impedances between stages of a radio frequency amplifier may be effected, thus enabling the amplifier to be operated at optimum efficiency. It is another object of my invention to provide a system which is relatively free from the use of choke coils, blocking condensers and the like.

My invention will be best understood upon reference to the accompanying drawing in which—

Figure 1 is a diagrammatic showing of a circuit which is referred to in the following discussion of the theory of operation of my invention; and

Fig. 2 illustrates diagrammatically a preferred circuit arrangement of the invention.

Referring first to Fig. 1, I show a pair of amplifier tubes 1 and 2, coupled by what is essentially a well known impedance matching network, sometimes called a "pi" network. The anode 3 of the tube 1 is fed with suitable direct current anode potential through a choke coil 4. The input energy applied to the grid 5 is amplified and impressed across the capacitor B, also across an inductive impedance L₁ to the grid 7 of the tube 2. The anode 8 of this tube feeds output energy to any suitable utilization device which may, of course, be a further stage of amplification or an antenna system if desired. The coupling network may be adjusted by means of a capacitor K on the input side of the inductive impedance L₁ and the capacitor C on the output side thereof. The grid 7 of the tube 2 may be suitably biased as by means of a biasing potential source 10 in circuit with a choke coil 9.

In using the circuit of Fig. 1, the capacitor C is set first to a relatively large value and then the capacitor K is adjusted so as to make the load impedance into which tube 1 works a pure resistance. If this resistance is then found to be too large for efficient energy transfer from the source of current then the capacitor C is adjusted to a smaller value and the capacitor K readjusted to again give a pure resistance loading. This operation can be repeated until the right value of the capacitor C is obtained for giving the desired loading of tube 1.

The circuit as shown in Fig. 1 may be used either in class B or in class C amplifiers. In either case there is a grid current which presents

a resistive load to the output of the network. It will be observed that the choke coils 4 and 9 and the blocking condenser B are required in order to permit suitable energizing of the tube electrodes, but that this makes the arrangement undesirable.

According to the present invention the arrangement of Fig. 2 has been found to give satisfactory service and without sacrifice of any of the advantages of the system shown in Fig. 1. The principal advantage to be derived from the circuit of Fig. 2 is that no choke coils or blocking condensers are required. This circuit looks like a pair of tuned coupled circuits of the ordinary variety, but upon further scrutiny of the diagram in the light of the discussion to follow, it will be seen that a number of important advantages are to be derived.

In this figure parts similar to those of Fig. 1 are given like reference characters. However, the elimination of choke coils and blocking condensers results from using a coupling transformer 12. The primary L' of this transformer is shunted by a capacitor K, whereas the secondary L'' is shunted by a capacitor C.

It is important that the coupling of the transformer 12 should be made very much closer than by any value ordinarily used in tuned networks, but not so close as would be obtained in an ideal transformer. The capacitors are not used to tune the coils but to match the impedances. The method of adjustment is quite similar to that hereinabove described in respect to Fig. 1, that is to say, the value of the capacitor C is first made very large, then the value of the capacitor K is adjusted to make the input impedance a pure resistance. Assuming that this resistance turns out to be larger than desired then the next step is to reduce the value of the capacitor C and subsequently to readjust the value of the capacitor K. This operation is repeated until the input resistance is of the desired value.

The mathematical basis for making the adjustments as aforesaid will now be considered.

When the value of the capacitor K is adjusted to make the input impedance of the network shown in Fig. 1 a pure resistance then the input conductance of this network has a value of

$$\frac{R}{\omega^2 L_1^2 + R^2 (1 - \omega^2 C L_1)^2}$$

where 1/R is the conductance of the utilization circuit into which the network delivers energy.

Correspondingly when the capacitor K, as shown in Fig. 2, is adjusted to make the input of

the network a pure resistance then the input conductance of this network has a value

$$\frac{k^2 R}{\omega^2 L_e^2 + R^2 (1 - \omega^2 C L_e)^2}$$

where k is the coefficient of coupling between the primary and secondary coils of the transformer 12 and $L_e = L(1 - k^2)$, and $L = L' = L''$.

It is not essential that the primary and secondary coils of the transformer 12 should be equal, but the equations are thereby simplified. If they are equal then the input conductance as given by the above expression in respect to Fig. 2 is obviously identical in form with the expression for the input conductance expressed in reference to the network of Fig. 1. If we choose the values of k and L , respectively, so that $L_e = L_1$ then the two expressions have the constant ratio k^2 .

Referring now to Fig. 2 and to the general case where the two coils are not necessarily equal, the load R will be properly matched to the internal resistance G of an alternating current source of a given frequency, as for example, the discharge tube 1, when the capacitors C and K are chosen to satisfy the following equations:

$$\frac{L'}{L'' k^2 R} \left[\omega^2 [L''(1 - k^2)]^2 + R^2 \{1 - \omega^2 C [L''(1 - k^2)]\}^2 \right] = G$$

and

$$K = \frac{1}{\omega^2 L'(1 - k^2)}.$$

$$\frac{\omega^2 L''^2 (1 - k^2)}{R^2} + (\omega^2 C L'' - 1) \{ \omega^2 C L'' (1 - k^2) - 1 \}$$

$$\frac{\omega^2 L''^2 (1 - k^2)}{R^2} + \left(\omega^2 C L'' - \frac{1}{1 - k^2} \right) \{ \omega^2 C L'' (1 - k^2) - 1 \}$$

It will be appreciated by those skilled in the art that my invention can be applied in numerous forms of radio circuits and its scope is therefore limited only in accordance with the definition of the claims.

I claim:

1. A network for converting an alternating current load impedance having conductance $1/R$ into a pure resistance of a desired value G comprising a secondary condenser connected across said load to make a total effective capacity C_2 across the conductance of said load, a secondary coil of inductance L_2 connected across said load, a primary coil of inductance L_1 arranged to be inductively and relatively closely coupled to said secondary coil, and a primary condenser connected across said primary coil to make a total capacity C_1 across said primary coil, said capacities being chosen to satisfy the equations

$$\frac{L_1}{L_2 R K} \left[\omega^2 [L_2(1 - k^2)]^2 + R^2 \{1 - \omega^2 C_2 [L_2(1 - k^2)]\}^2 \right] = G$$

and

$$C_1 = \frac{1}{\omega^2 L_1(1 - k^2)}.$$

$$\frac{\omega^2 L_2^2 (1 - k^2)}{R^2} + (\omega^2 C_2 L_2 - 1) \{ \omega^2 C_2 L_2 (1 - k^2) - 1 \}$$

$$\frac{\omega^2 L_2^2 (1 - k^2)}{R^2} + \left(\omega^2 C_2 L_2 - \frac{1}{1 - k^2} \right) \{ \omega^2 C_2 L_2 (1 - k^2) - 1 \}$$

wherein k represents the coefficient of coupling between primary and secondary coils L_1 and L_2 and ω represents the frequency of said alternating current multiplied by 2π .

2. An impedance matching network as defined in claim 1 in which the coefficient of coupling

between the primary and secondary coils is at least 15 percent and not greater than 80 percent.

3. An impedance matching network as defined in claim 1 in which the coefficient of coupling between the primary and secondary coils approaches 40 to 50 percent as an optimum value.

4. A reactance network for matching the impedance of a load to that of a source of alternating currents, comprising a variable capacitor C connected across the load, a transformer having a secondary coil L'' connected to the terminals of said load and a primary coil L' connected to said source, and a variable capacitor K connected across said primary coil and so adjusted as to absorb wattless current drawn by said primary coil, said transformer having a coefficient of coupling k between its coils, said coefficient being of such value as to produce two natural frequencies, one of which is outside the band of frequencies to be amplified, and said capacitors and transformer coils having values so chosen as to obtain a substantially pure input resistance in the network per se, while the conductance of said network has a value

$$\frac{k^2 R}{\omega^2 L_e^2 + R^2 (1 - \omega^2 C L_e)^2} = \frac{1}{G}$$

where $L_e = L(1 - k^2)$ and $L = L' = L''$, and wherein G is the internal resistance of said source.

5. In a reactance network fed by a source of alternating currents and feeding into a load, such network being constituted by a transformer having its primary shunted by a variable capacitor and its secondary shunted by a second variable capacitor, said transformer having a relatively high coefficient of coupling, the method of matching the overall impedance of the load and the network to said source of alternating currents which comprises adjusting the second capacitor to a relatively large value, adjusting the first capacitor so as to make the load impedance a substantially pure resistance, then reducing the capacity of the second capacitor and readjusting the first capacitor in the order named until an efficient transfer of energy is obtained from said source to said load while maintaining said load as a substantially pure resistance.

6. A reactance network fed by a source of alternating current of a given frequency, which source has an internal resistance G , said network feeding into a load resistance R and comprising a transformer having a primary coil connected to said source and a secondary coil connected to said load resistance, the inductances of said primary and secondary coils respectively being of values designated L' and L'' , said transformer having a coefficient of coupling k between its primary and secondary coils, a capacitor having a capacitance value K connected across said primary coil, another capacitor having a capacitance value C connected across said secondary coil, and said network being so characterized as to satisfy the following equation:

$$\frac{k^2 R}{\omega^2 L_e^2 + R^2 (1 - \omega^2 C L_e)^2} = \frac{1}{G}$$

wherein $L_e = L(1 - k^2)$, where $L = L' = L''$, and wherein G is the aforementioned internal resistance.
